(57) **CLAIM**

We claim the ornamental design for box for feeding animals, as shown and described.

DESCRIPTION

FIG. 1 is a front perspective view of an example of the box for feeding animals.

FIG. 2 is a front view of the example of the box for feeding animals.

FIG. 3 is a back view of the example of the box for feeding animals.

FIG. 4 is a right side view of the example of the box for feeding animals.

FIG. 5 is a left side view of the example of the box for feeding animals.

FIG. 6 is a top view of the example of the box for feeding animals.

FIG. 7 is a bottom view of the example of the box for feeding animals; and,

FIG. 8 is a top view of the box for feeding animals prior to assembly of the box for feeding animals into the shape illustrated in FIGS. 1-7.

It is understood that portions of the carton shown in long broken lines (— — —) represent perforations, which form part of the claimed design. It is also understood that the following pattern (— — — —) represent perforations, which form no part of the claimed design.

1 Claim, 5 Drawing Sheets
